ELECTRIC OVEN AND STOVE COMBINATION

Ray C. Sandin, Northbrook, Ill., assignor to General
Electric Company, a corporation of New York

Application October 19, 1956, Serial No. 43,416

Term of patent 14 years

(Cl. D81—4)

Fig. 1 is a front perspective view of an electric oven and stove combination embodying my new design; and Fig. 2 is a rear perspective view thereof.

The design is characterized by the stove unit at the side in combination with the oven unit.

I claim:

The ornamental design for an electric oven and stove combination, substantially as shown and described.
